POWER LAWN MOWER

Marnie C. Averitt, Timonium, and James E. Dickson,
Towson, Md., assignors to The Black and Decker Man-
ufacturing Company, Towson, Md., a corporation of
Maryland

Filed Oct. 31, 1966, Ser. No. 4,483

Term of patent 14 years

(Cl. D40—1)

FIG. 1

FIG. 2

FIG. 3

FIG. 4FIG. 5FIG. 6FIG. 7FIG. 1 is a perspective view of a power lawn mower showing our new design; the opposite side of the mower handle is substantially the same as the side shown;

FIG. 2 is a top plan view drawn to an enlarged scale of the power lawn mower shown in FIG. 1, the end handle being removed for ease of illustration;

FIG. 3 is a bottom plan view thereof;

FIG. 4 is a right side elevation;

FIG. 5 is a left side elevation;

FIG. 6 is a front elevation; and

FIG. 7 is a rear elevation.

The dominant features of my design reside in the portions shown in full lines.

We claim:

The ornamental design for a power lawn mower, as shown and described.
